UNITED STATES PATENT OFFICE.

SOLOMON SHAPIRO, OF NEW YORK, N. Y., ASSIGNOR TO RELIANCE METAL SPINNING COMPANY, OF NEW YORK, N. Y., A COPARTNERSHIP COMPOSED OF SAMUEL SHAPIRO, JOSEPH SHAPIRO, SOLOMON SHAPIRO, DAVE SHAPIRO, AND MORRIS BERMAN.

DESIGN FOR A BODY FOR ELECTRIC FIXTURES.

48,833.

Specification for Design.

Patented Apr. 4, 1916.

Application filed November 20, 1915. Serial No. 62,643. Term of patent 3½ years.

To all whom it may concern:

Be it known that I, SOLOMON SHAPIRO, a subject of the Czar of Russia, residing in the city of New York, borough of Brooklyn, in the county of Kings and State of New York, have invented a new, original, and ornamental Design for a Body for Electric Fixtures, of which the following is a specification, reference being had to the accompanying drawing, forming part thereof.

The figure is a perspective view of a body for electric fixtures, showing my design.

The design comprises an electric fixture having a body formed with a comparatively large bulged central portion 1 from which extends a bead 2 which in turn has extending therefrom a rounded upper portion 3

terminating in a stem 4. The bulged portion 1 has extending therefrom a ring-shaped section 5 having ornamental projections 6 thereon, the ring-shaped portion 5 being bent so as to form a recess 7 and a downwardly projecting substantially conical-shaped portion 8, which in turn has projecting therefrom an inverted cup-shaped bottom 9 having ornamental ribs provided thereon.

I claim:

The ornamental design for a body for electric fixtures, as shown and described.

SOLOMON SHAPIRO.
